MACHINE FOR THE COATING OF WEBS OF MATERIAL

Arthur Ronald Trist, St. Catherines, Ontario,
CanadaApplication November 25, 1949, Serial No. 129,289
In Great Britain December 23, 1948

7 Claims. (Cl. 118—409)

1

The invention relates to improvements in machines for the coating of webs of material and has particular reference to coating machines in which a web of material is coated with a composition over a given width and passed between a stationary trailing blade and a resilient moving bed the blade and bed being adjusted relatively to one another to produce a continuous layer of the coating substance on the web from a fountain formed by the surface of the web supported by the bed, and the surface of the blade, the width of the coated surface being controlled by dykes that are adjustably mounted on the fountain and have surfaces in close proximity with or even touching the moving web.

The invention has for its object to provide means whereby irregular wear of the blade is avoided, the body of the coating applied to the web of material is maintained of even thickness and the thickness of each margin of the coating is equal to or less than that of the body of the coating to avoid objectionable stressing or straining of the margin of the web of coated material during re-reeling.

This invention consists in a machine for the coating of webs of material comprising a resilient moving bed supporting the web of material, a fountain for the coating composition having a floor at its lower part to form a stock for a stationary elastic trailing blade for controlling the application of the composition and dykes for limiting the width of the fountain for the coating composition and is characterised in that the length of the blade is less than the distance between the outer edges of the dykes and that the corners where the blade, the facing surfaces of the dykes and the surface of the web meet are sealed against liquid leakage by angular elements each of which rests on the floor of the fountain, has a surface adjacent to a facing wall of a dyke and has a metering surface arranged to be adjacent to the web but not in contact therewith.

In the drawings:

Figure 1 is a fragmentary perspective elevation of part of a coating machine of the kind to which this invention relates and which is pertinent to the description;

Figure 2 is a fragmentary exaggerated side elevation of a worn blade;

Figure 3 is a diagrammatic plan view of an ineffective arrangement having a blade the length of which is equal to the distance between the facing surfaces of the dykes;

Figure 4 is a diagrammatic plan view of an arrangement having a blade the length of which

is less than the distance between the outer edges of the dykes;

Figure 5 is a diagrammatic plan view of an arrangement having a blade the length of which is less than the distance between the facing surfaces of the dykes;

Figure 6 is a side elevation of one form of protector;

Figure 7 is an end elevation of Figure 6;

Figure 8 is a plan view of Figure 6;

Figure 9 is a side elevation of another form of protector;

Figure 10 is an end elevation of Figure 9;

Figure 11 is a plan view of Figure 9;

Figure 12 is a fragmentary plan view of a coating machine showing a method of mounting a protector of the kind shown in Figures 6, 7 and 8;

Figure 13 is a fragmentary side elevation of a coating machine partly in section to show a method of mounting a protector of the kind shown in Figures 9, 10 and 11;

Figure 14 is a cross section through a margin of a coated web drawn to an exaggerated scale;

Figure 15 is a side elevation of a pneumatic protector and

Figure 16 is a side elevation of an inflatable member to be interposed between the under side of a protector and the floor of the fountain.

When the moving bed is a resilient cylinder or roller 1 covered with resilient material i. e. a layer 10 of india rubber as shown in Figure 1 and the coating composition is abrasive, the edge 2 of the very thin steel blade 3 e. g. about one hundredth of an inch in thickness, is worn away irregularly somewhat as shown to an exaggerated extent in Figure 2.

The end parts 4, 4 of the blade 3, protected by and extending beyond the dykes 5, 5 (shown dotted in Figure 2) are affected to a very much less extent (if at all) than the operative part 6 between the dykes 5, 5 whilst the parts 7, 7 of the edge immediately within the dykes 5, 5 are affected to a greater extent than the part 6 owing to the severity of the scouring action of the stream of composition produced in the two outer corners of the fountain at the parts of the surface of the web to contact with the blade 3 and a dyke 5.

The result of the above described actions quickly renders the edge 2 of the blade 3 useless until it has been reground to restore the straight edge thus necessitating expensive servicing at short intervals and/or frequent replacement either of which involves the laborious and difficult steps of stopping and starting the machine.

If to avoid the above defect the parts 4, 4 of

3

the blade 3 are cut away another difficulty is introduced because, on the one hand, if to avoid leakage the length of the blade 3, is made exactly similar to the distance between the facing surfaces 51, 51 of the dykes 5, 5 the heat generated by the operation of the machine causes the blade 3, which may be of any length and sometimes is some sixteen feet or so in length and as stated above about one hundredth of an inch in thickness, to expand longitudinally to such an extent that the edge 2 buckles (as crudely shown in Figure 3) so that the thickness of the coating 111 varies across the width and the coated material is useless, and on the other hand, if to avoid buckling the length of the blade 3 is made less than the distance between the facing surfaces 51, 51 of the dykes 5, 5 the leakage through the gaps 8, 8 between the ends of the blade 3 and the facing surfaces 51, 51 of the dykes 5, 5 causes a thickening of the margins 112, 112 of the coating 111 (as shown to exaggerated degrees in Figure 5) that in practice prevents the coated material from being re-reeled without unduly stretching the margins of the web 11 with the result that when the coated web is re-reeled, the reel is not cylindrical.

The difficulties explained above can be avoided if the length of the blade 3 is made less than the distance between the outer edges 52, 52 of the dykes 5, 5 to expose a part of the surface 53 on each dyke 5 to such an extent that the margins of the coating 111 are smoothed or metered to prevent the undesirable thickening 112 as shown in Figure 14.

As shown in Figure 4 the length of the blade 3 is less than the distance between the outer edges 52, 52 of a pair of dykes 5, 5 but is more than the distance between the facing surfaces 51, 51 of a pair of dykes 5, 5 whilst as shown in Figure 5 the length of the blade 3 is less than the distance between the facing surfaces 51, 51 of a pair of dykes 5, 5 thus leaving the gaps 8, 8 between the ends of the blade 3 and the facing surfaces 51, 51 of the dykes 5, 5.

In the first alternative the deflection of the ends of the blade 3 incidental to the movement of the web 11 would cause leakage at the corner 9 where the surface of the web 11, the blade 3 and the surfaces 51, 51 of the pair of dykes 5, 5 meet whilst in the other alternative the unavoidable gaps 8, 8 also would cause leakage at the corners 9, 9 referred to.

In both these alternative arrangements leakage is obviated by filling up the corners 9, 9 with angular elements or protectors that act as throttles and also act to deflect the streams of composition, that by abrasive action produce the excessively worn parts 7, 7 of the blade 3, harmlessly into the fountain.

The deflection of the ends of the blade 3 is due to the pressure exerted at those points by the coating composition that is crowded endwise by the movement of the web 11 so that in the first alternative the protectors by throttling the flow of composition tend to reduce the deflection and thus reduce the leakage to a quantity that can be spread, by the parts of the surfaces 53, 53 of the dykes 5, 5 that extend beyond the ends of the blade 3, evenly on the web 11 without surplus whereas in the second alternative the flow of composition is throttled to reduce the leakage to a quantity that can be spread by the whole of the surfaces 53, 53 of the dykes 5, 5 evenly on the web 11 again without surplus.

4

Each protector consists of a block 12 of any material, e. g. metal, rubber (natural or synthetic) or a synthetic composition, that is not deleteriously affected by any of the oils or solvents contained in the coating composition that may be of the kind that is not water-wetting and has an obliquely curved face 13, i. e. a curved face that approaches the web 11 on the roller 1, indicated by a chain line in Figures 6 and 9, obliquely; as shown in Figure 7 the obliquely curved face 13 is quasitriangular and as shown in Figure 10 the face 13 is substantially rectangular.

The shape of the remainder of the block 12 as a whole has to meet certain requirements, that is to say, there must be a somewhat flat surface 14 that can be arranged adjacent to a vertical facing wall 51 of a dyke 5 and a lower surface 15 profiled to fit the upper surface of the floor 20 of the fountain and the upper surface of the scraper blade 3 when the machine is at rest.

Generally the blocks 12, 12 are wholly submerged in the coating composition in the fountain, although this is not strictly essential, with the curved faces 13, 13 adjacent to the web 11 on the roller 1 but oblique thereto, that is to say, with the tips 121, 121 of the blocks 12, 12 located in the corners 9, 9, at about one hundredth of an inch away from the surface of the web 11 (when of paper) on the roller 1 whilst the more remote part 122 of the block 12 is about one fiftieth part of an inch away from the surface of the web 11 (when of paper) but these distances are not definite as they depend on the nature of the web 11, the speed of movement of the web 11 and the character of the emulsion. In no circumstances in any part of a block 12 in contact with the surface of the web 11.

The adjustment of the blocks 12, 12 on the dykes 5, 5 as shown in Figures 6, 7, 8 and 12 is simple but apt to be somewhat insufficient because the obliquity of the face 13 is more or less fixed. In this arrangement each block 12 is mounted on a stud 21 that passes through a slotted hole 22 in a dyke 5 and is provided with a nut 23 by which the block 12 can be locked in adjusted position.

The stud 21 is embraced by the eye 24 of the screwed stem 25 that passes through the back wall 201 of the fountain and is fitted with a nut 26 that is restrained from endwise movement by the back wall 201 of the fountain and the bridle 27 to enable the block 12 to be advanced and withdrawn from the surface of the roller 1 with micrometric exactitude, a liquidtight joint between the surface 15 and floor 20 being maintained by the sole 151 of flexible material e. g. india rubber, that is mounted on the under side of the block 12 and profiled at 15 to conform with the surface of the floor 20.

The arrangement shown in Figure 13 provides for greater universality of adjustments, each block 12 being mounted on the end of a stalk or stem 30 that is a loose fit in the hole 31 of the angle bracket 32 mounted on the outer surface 52 of a dyke 5 by welding or by screws 54.

The upper end 33 of each stem 30, that passes through a hole 31, is screw threaded and fitted with upper and lower finger nuts 34 and 35 respectively to enable exact adjustments of the block relative to the surface 51 and on the floor 20 to be made and to provide for a small angular adjustment of the stem 30 spherical washer assemblies 36, 36 are located between the finger nuts 34 and 35 and the bracket 32.

With the above adjustments it will be seen that

a block 12 can be advanced towards and withdrawn from the surface of the web on the roller 1 sufficient distances to effect adjustment whilst the machine is in operation and that if the block 12 is tilted slightly on the upper surface of the floor 20 of the fountain there is no liquid leakage because the block 12 has a sole 151 of flexible material that is sufficiently soft for the accommodation likely to be required.

The obliquity of the face 13 of each block 12 relatively to the surface of the web 11 and the floor 20 of the fountain is so proportioned that on the one hand the surplus coating composition is diverted or the volume throttled and on the other hand just sufficient coating composition at 15 a proper velocity to provide the required width or natural spread of coating 111 on the web 11 by a dyke 5, is induced into the gap between the oblique face 13 and the surface of the web 11 and evenly distributed by the travel of the web 11 20 relatively to the blade 3 and dykes 5, 5.

As previously explained the lower part or surface 15 of each of the blocks 12 is profiled to conform with the floor 20 of the fountain, that acts as a stock for the blade 3, and with the upper 25 surface of the blade 3 when the machine is at rest and usually has a soft packing layer 151 to prevent leakage whilst the surface 14, is close to or in contact with a facing surface 51 of a dyke 5, so that any gaps e.g. the gaps 8, 8 between the 30 ends of the blade 3 and the facing surfaces of the pair of dykes 5, 5 or the gaps produced by deflection of the blade 3 from the surface 15 when the machine is in operation, are effectively sealed, the blade 3 being allowed to expand longitudinally without restraint so as to avoid any cause 35 likely to buckle the edge 2.

In certain cases it is advisable to use a more developed form of seal between the surfaces 15 and floor 20 and to this end the block 12 may be formed with a cavity 123 open to the under surface as shown in Figure 15 to enable the sole 151 of flexible material to be distended slightly by 40 pneumatic pressure applied through the automobile tire valve 124 and stem 301, that is in the form of a tube in this case, by a tire inflator e.g. 45 125.

When considerable air pressure is found to be necessary the sole 151 may be formed as an inflatable member 152 of flexible material having a lower face 153 to conform to the floor 20 and blade 3 and an upper face 154 to conform to the under side of the block 12 to which it may be attached.

The provision of means by which the pressure of the sole on the floor of the fountain can be varied within considerable limits enables more accurate adjustment of the protectors to be effected as the contact pressure on the floor 20 temporarily can be reduced whilst the block 12 is adjusted and tilted to get the best effect and then the pressure can be increased to obtain a large area seal free from disturbing forces.

As the blade 3 can expand longitudinally without constraint between the facing surfaces 51, 51 of the dykes 5, 5 as shown in Figure 5 or over the surfaces 53, 53 of the dykes 5, 5 as shown in Figure 4 and, owing to the blocks 12, 12 the edge 2 of the blade 3 is affected equally by the abrasive action of the coating composition, leakage is 70 avoided, the proper width of coating 111 is evenly applied to the web 11, and the streams of composition at the dykes 5, 5 are diverted so that the margins 112, 112 of the coating 111 are not thickened and the undue wear at 7, 7 (see Figure 75

2) is avoided with the result that the blade 3 can be advanced from time to time to compensate for wear until it becomes too narrow to be held in the stock.

5 I claim:

1. Means for controlling the leakage of liquid from the ends of the fountain for the coating composition in a coating machine having a resilient moving bed supporting the web of material to be coated, a floor for the lower part of the fountain to form a stock for a stationary elastic trailing blade and dykes for limiting the width of the fountain, comprising a stationary elastic trailing blade of less length than the distance between the outer edges of the dykes mounted on the floor of the fountain, an angular element resting on the floor of the fountain adjacent to the facing surface of each dyke and a metering surface on the angular element adjacent to the web but not in contact therewith.

2. Means for controlling the leakage of liquid from the ends of the fountain for the coating composition in a coating machine having a resilient moving bed supporting the web of material to be coated, a floor for the lower part of the fountain to form a stock for a stationary elastic trailing blade and dykes for limiting the width of the fountain, comprising a stationary elastic trailing blade of less length than the distance between the outer edges of the dykes mounted on the floor of the fountain, an angular element resting on the floor of the fountain adjacent to the facing surface of each dyke, a cavity in the underside of each element, a layer of flexible material attached to the underside of each element to seal the cavity, a conduit for admitting air under pressure into the cavity to distend the flexible material into jointing coaction with the floor, and a metering surface on the angular element adjacent to the web but not in contact therewith.

3. Means for controlling the leakage of liquid from the ends of the fountain for the coating composition in a coating machine having a resilient moving bed supporting the web of material to be coated, a floor for the lower part of the fountain to form a stock for a stationary elastic trailing blade and dykes for limiting the width of the fountain, comprising a stationary elastic trailing blade of less length than the distance between the outer edges of the dykes mounted on the floor of the fountain, an angular element resting on the floor of the fountain and slidably mounted on the facing surface of each dyke, micrometric means for adjusting the angular element on the dyke, clamping means for holding each angular element in adjusted position, flexible packing between the under side of each angular element and the floor of the fountain, and a metering surface on each angular element obliquely adjacent to the web but not in contact therewith.

4. Means for controlling the leakage of liquid from the ends of the fountain for the coating composition in a coating machine having a resilient moving bed supporting the web of material to be coated, a floor for the lower part of the fountain to form a stock for a stationary elastic trailing blade and dykes for limiting the width of the fountain, comprising a stationary elastic trailing blade of less length than the distance between the outer edges of the dykes mounted on the floor of the fountain, an angular element resting on the floor of the fountain in proximity to each facing surface of the dykes,

a screwed supporting stem for each element, an angle bracket on each dyke with a hole to receive the stem, a first spherical assembly on each stem above the bracket, a second spherical assembly on each stem below the bracket, a first clamping nut on each screwed stem above the first spherical assembly, a second clamping nut on each screwed stem below the second spherical assembly, flexible packing between the under side of each angular element and the floor of the fountain and a metering surface on each angular element obliquely adjacent to the web with the points of the surfaces nearest to the ends of the blade closest to the web but not in contact therewith.

5. Means for controlling the leakage of liquid from the ends of the fountain for the coating composition in a coating machine having a resilient moving bed supporting the web of material to be coated, a floor for the lower part of the fountain to form a stock for a stationary elastic trailing blade and dykes for limiting the width of the fountain comprising a stationary elastic trailing blade of less length than the distance between the outer edges of the dykes mounted on the floor of the fountain, an angular element resting on the floor of the fountain in proximity to each facing surface of the dykes, a screwed supporting tubular stem for each element, an

10
5

inflator valve in the upper part of each stem, a downwardly opening cavity in each element, a flexible chamber in each cavity jointed to the tubular stem adapted to be inflated into jointing coaction with the floor of the fountain, an angle bracket on each dyke with a hole to receive the stem, spherical assemblies on each stem above and below the bracket, a first clamping nut on each stem above the upper spherical assembly, a second clamping nut on each stem below the lower spherical assembly, and a metering surface on each angular element obliquely adjacent to the web with the points of the surfaces nearest to the ends of the blade closest to but not in contact with the web.

15 6. In means for controlling the leakage of liquid as claimed in claim 1 the arrangement of the metering surfaces on the angular elements obliquely to the surface of the web with the 20 corners nearest to the ends of the blade closest to the surface of the web.

7. In means for controlling the leakage of liquid as claimed in claim 1 the arrangement of a layer of flexible jointing material on the 25 under surface of the angular element that rests on the floor of the fountain.

ARTHUR RONALD TRIST.
